UNITED STATES PATENT OFFICE.

CROMWELL O. CASE, OF NEW BRITAIN, CONNECTICUT, ASSIGNOR TO P. & F. CORBIN, OF SAME PLACE.

DOOR-KNOB.

SPECIFICATION forming part of Letters Patent No. 409,010, dated August 13, 1889.

Application filed May 16, 1889. Serial No. 310,968. (No model.)

To all whom it may concern:

Be it known that I, CROMWELL O. CASE, a citizen of the United States, residing at New Britain, in the county of Hartford and State 5 of Connecticut, have invented certain new and useful Improvements in Cast-Metal Door-Knobs, of which the following is a specification.

My invention relates to improvements in 10 hollow cast-metal door-knobs; and the chief object of my invention is to produce a substantial hollow knob in which the parts are firmly forced and held together.

In the accompanying drawings, Figure 1 is 15 a vertical section of the parts composing my knob, the same being placed together without being secured; and Fig. 2 is a like view of my knob in its finished form.

The general form of the knob is old, 20 consisting of the ordinary oval form as viewed in the drawings, and when viewed in end view of the ordinary round form.

A designates one part of the shell, provided 25 with the ordinary knob-shank B, the shell portion consisting of a cup or saucer shaped part with a plain edge in the ordinary form for such parts.

C designates the cap portion of the shell, which I provide with the ordinary flange 3, 30 for being turned down upon the exterior of the part A in the ordinary manner. In addition to these ordinary parts I provide the cap C with an internal flange 4, leaving an annular space between the flanges 3 and 4 for the 35 edge of the part A to set into. The flange 4 should be of such a size and projection as to

extend somewhat into the interior of the part A and snugly fill the same. The parts are then put in a lathe or special machine, firmly held together therein, and the flange 3 bent 40 or spun firmly down upon the part A, as shown in Fig. 2. The cap C being formed of cast metal, a powerful pressure is required in order to spin down the flange 3 so as to set it firmly against the part A and make a close 45 joint. The internal flange 4 holds the edge of the part A in place and prevents it from bending inwardly under the diametrical pressure of the spinning-tool, whereby I am enabled to firmly force the parts together, so as 50 to form a firm union and a close joint by pressure.

I am aware that a knob of substantially the same general character as the one herein shown, without the internal flange 4 and the 55 annular space defined on the inside by said flange, is old, and such a knob is hereby disclaimed.

I claim as my invention—

The herein-described door-knob, consisting 60 of an ordinary half-shell A and knob-shank B, and the cap part C of the shell, provided with the internal flange 4 and ordinary external flange 3, and an annular space between 65 said flanges, into which the edge of the half-shell A sets, substantially as described, and for the purpose specified.

CROMWELL O. CASE.
